UNITED STATES PATENT OFFICE.

GEORGE W. NEWTON AND ALBERT M. CARL, OF NEWTON, IOWA.

SHADE-BRACKET.

No. 836,602.

Specification of Letters Patent.

Patented Nov. 20, 1906.

Application filed March 23, 1905. Serial No. 251,654.

To all whom it may concern:

Be it known that we, GEORGE W. NEWTON and ALBERT M. CARL, citizens of the United States, residing at Newton, in the county of 5 Jasper and State of Iowa, have invented new and useful Improvements in Shade-Brackets, of which the following is a specification.

The invention relates to an improvement in shade-brackets, and particularly to a 10 bracket made of a single length of material and designed to efficiently support the ends of the roller.

The main object of the invention is to provide a bracket particularly adapted for attachment with the spring end of the roller, constructed and arranged to readily receive the journal of said end and prevent its accidental disengagement therefrom.

The invention will be described in detail 20 in the following specification, with particular reference to the accompanying drawing, in which the figure is a perspective view of my improved bracket, the shade being shown in dotted outline.

25 Referring to the drawing, 1 represents the shade-bracket having at one end the usual squared spring-shaft 2 and at the opposite end the stud-journal 3. The bracket for the spring-shaft 2 is preferably constructed of 30 a single length of wire 4, sharpened and threaded at one end, as at 5, the opposite end being bent downwardly at a right angle, as at 6, then forwardly at a right angle, as at 7, then upwardly at a right angle, as at 8, the 35 part 8 being projected above the body 4 of the bracket and bent rearwardly, as at 9, in alinement with and spaced above the body 4.

In use the brackets are arranged with suitable relation to the window-casing and the 40 length of the shade-roller, and the stud 3 of the roller is inserted into the eye 12 of the bracket 10. The rectangular end 2 of the spring-shaft is then inserted in the bracket 4, being arranged to rest between the arms 45 6 and 8 of the bracket and rest upon the portion 7 thereof, it being understood that the arms 6 and 8 are spaced apart a distance to receive the rectangular end of the spring-shaft 2 and hold the same against rotation. 50 In practice the pull upon the spring-shade

necessary to release the dogs from their catches and set the spring in operation is usually sufficient to jar or dislodge the end of the shaft 2 from its bracket when the pull is released to elevate the curtain, and to prevent such accidental disengagement we provide the bracket with the overhang or guard 55 9, against which the spring contacts should it accidentally move upward, whereby its disengagement from the bracket is prevented. 60

It is understood that the distance between the body 4 and the overhang-guard 9 of the bracket is less than the vertical length of the rectangular end of the squared shaft, so that there is no possibility of the disengagement 65 of the spring-shaft from the bracket without the turning of the latter.

By preference the brackets are each made of a single length of wire, though it is understood that other material may be used, if desired. 70

Having thus described the invention, what we claim as new is—

A shade-bracket of integral formation having a shank member threaded at one end and 75 bent at its opposite end at right angles to said member, the bracket at the terminal of said right-angled portion being projected forwardly in parallel relation with the shank, then upwardly in parallel relation with the 80 right-angled portion, said upward projection extending above the shank and being terminally bent rearwardly in spaced parallel relation to the shank, said rearward extension terminating in rear of the right-angled portion and being spaced from the shank a distance less than the length of said right-angled portion, whereby the shank and said rearwardly-projecting portion form an entrance-opening disposed at right angles to the 85 roller-pintle-receiving space formed between the right-angled portion and upwardly-projected portion. 90

In testimony whereof we affix our signatures in presence of two witnesses.

GEORGE W. NEWTON.
ALBERT M. CARL.
